HEMMER ATTACHMENT

George Westhoff, Millstadt, Ill.

Application September 5, 1941, Serial No. 409,621

5 Claims. (Cl. 112—141)

The present invention relates generally to attachments for sewing machines and more particularly to a hemmer employed with sewing machines.

An object of the present invention is to provide a novel hemmer attachment for sewing machines which is adapted to make a single needle fell seam.

Another object is to provide a novel hemmer attachment for sewing machines which is constructed to accept and pass to the needle a cross seam or other thickness of cloth without slowing down or jamming the movement of the cloth.

Another object is to provide a novel hemmer attachment for sewing machines which is adapted to speed up the production of the machines to which it is attached.

Another object is to provide a novel hemmer attachment for sewing machines which is constructed to readily receive cloth threaded therein and to fold and pass the same to an adjacent needle at a high speed and without diminution thereof regardless of folds, cross seams, or the like.

Other objects are to provide a hemmer attachment for sewing machines which is sturdy in construction, simple to apply, and positive in its operation.

Still other objects and advantages are apparent from the following description taken in conjunction with the accompanying drawing in which:

Fig. 1 is a top plan view of a hemmer attachment embodying the concepts of the present invention;

Fig. 2 is a front elevation of the hemmer attachment shown in Fig. 1, a part of the support being broken away for conservation of space;

Fig. 3 is a side elevation of the hemmer attachment looking from the left of Fig. 1;

Fig. 4 is a rear elevation of the hemmer attachment;

Fig. 5 is a section on the line 5—5 of Fig. 1;

Fig. 6 is a front elevation of the hemmer attachment with the pivotal portion in spaced relationship to the stationary portion;

Fig. 7 is an enlarged plan view similar to Fig. 1 showing pieces of cloth in operative relation thereto, the hemmer attachment being disposed adjacent the needle of a machine;

Fig. 8 is a section on the line 8—8 of Fig. 7 showing how the cloth is rolled by the hemmer attachment;

Fig. 9 is a view of a segment of cloth after leaving the needle shown in Fig. 7;

Fig. 10 is a section on the line 10—10 of Fig. 9;

Fig. 11 is a view of the segment of cloth shown in Fig. 9, the top portion being pulled over relative to the bottom portion; and

Fig. 12 is a section on the line 12—12 of Fig. 11.

Referring to the drawing more particularly by

reference numerals, 15 indicates generally a hemmer attachment constructed in accordance with the teachings of the present invention. The hemmer attachment 15 includes a support 16 and a main body 17.

The support 16 comprises an elongated body portion 19 having a head portion 20 and a flange 21. The body portion 19 includes a side flange 22 and a slot 23.

10 The main body 17 includes an outer roll section 26 which is of the cross-section shown in Figs. 5 and 6 and which includes a trough 27 of narrowing cross-section from rear to front and a cloth receiving wall 28. The roll section 26 is secured directly to the flange 21 by welding, or the like.

15 A rear cloth guard 30 is secured to the roll section 26 near the rear end thereof, and a front cloth guard 31 is secured to the front end thereof. The guards 30 and 31 form, in effect, continuations of the end edges of the trough 27.

20 A stationary hinge extension member 34 is secured by welding, or the like, to the edge of the trough 27 between the cloth guards 30 and 31. A hinge 35 is welded or otherwise fixed to the hinge extension 34 by a lower hinge plate 36. An upper hinge plate 37 has secured thereto by welding, or the like, a hinge extension 38 of the same configuration as the hinge extension 34. The hinge extensions 34 and 38 have aligned slots 40 and 41, respectively (Figs. 3 and 5). A tension spring 42 is suspended in the slots 40 and 41, being connected at its ends to oppositely extending projections 43 and 44 which are formed integral with the hinge extensions 34 and 38, respectively.

25 A forming hemmer section 47 is welded or otherwise secured to the free end of the hinge section 38 and is disposed to complement the trough 27. The forming hemmer section 47 is of the configuration shown in the drawing, and includes a wall 48 of inverted converging concave cross-section which forms, in effect, a continuation of the trough 27 (Figs. 2 and 5). A rearwardly disposed secondary trough 49 which extends substantially half the length of the section 47 is spaced 30 from the rear portion of the trough 27 and extends outwardly therebeyond (Fig. 1).

35 A hinge extension guard 50 is welded or otherwise secured to the hinge extension 34.

Operation

40 In Fig. 7, the hemmer attachment 15 is shown mounted on a machine (not shown) in operative relation to a needle 52. Two pieces of cloth 53 and 54 are in the hemmer attachment 15 and extend 45 beyond the needle 52. It is to be observed that the cloth pieces 53 and 54 are disposed in flat relationship with the free edges aligned. The cloth pieces 53 and 54 thus related are fed into the hemmer attachment 15 with the free edges substantially touching the bottom of the secondary

trough 49. With the cloth pieces 53 and 54 fed in aforesaid, they emerge at the front end in the relationship shown in Fig. 8. The needle 52 passes through the cloth in such relationship to complete a fell seam.

Quite often it is necessary to seam across seamed portions or across multiple layers of cloth. Such cross seams and other increased thicknesses pass through the hemmer attachment 15 to the needle 52 without jamming and without slowing down the seaming operation. The forming hemmer section 47 yields outwardly when an increased thickness of cloth moves into the constricted portion of the attachment 15 due to the tension spring 42 and the hinge construction. Thus, with the hemmer attachment 15, the speed of the sewing machine, which may be 5,000 R. P. M., is fully maintained.

The cloth guards 30 and 31 are disposed to prevent the cloth pieces 53 and 54 from slipping between the hinge sections 34 and 38. The hinge extension guard 50 prevents the hinge section 38 from being pivoted in a vertical plane which would result from the continued force of the cloth moving through the hemmer attachment 15.

It is to be understood that the several elements described and shown may be varied as to configuration and material within the scope of the invention. For example, the hinge sections 34 and 38, and the hinge 35 may be made in two pieces if desired, and the projections 43 and 44 may be secured to the hinge extensions 34 and 38 rather than formed integral therewith.

It is also to be understood that the foregoing description and the accompanying drawing have been given by way of illustration and example and not for purposes of limitation, the invention being limited only by the claims which follow.

What is claimed is:

1. In a device of the kind described, a support, means for rolling cloth for seaming mounted thereon, comprising a stationary section and a pivotally mounted section, said two sections having complementary cloth rolling surfaces, separable at adjoining edges, said pivotally mounted section being adapted to yield away from the stationary section to separate said complementary surfaces and adjoining edges upon the passage through the device of an abnormal thickness of cloth, and a member connected at each end of the stationary section extending therefrom across the ends of the pivotally mounted section, said member being of sufficient length to extend across the space between the complementary surfaces when separated, and having an inner surface to join said surfaces whereby to prevent cloth from getting between the adjoining edges of the sections.

2. A hemmer attachment comprising a support, a stationary outer hemmer section mounted on the support, a hinge section secured to the outer hemmer section, a second hinge section pivotally associated with the first hinge section, a forming hemmer section secured to the free end of the pivoted hinge section and disposed in operative relationship to the outer hemmer section, and means biasing said pivoted hinge section into closed relationship with the stationary hinge section, said biasing means including a tension spring disposed at an angle to the hinge sections and extending through openings in each section substantially centrally of the ends thereof, said spring being anchored to a projection secured to each section.

3. In a hemmer for use on material of vary-

ing thickness, a first body portion comprising a wall providing a surface curved around from an outer part extending in one direction, to an inner part extending substantially in the opposite direction,

5 5 to provide a first trough section, said surface having a larger radius of curvature at one end of the trough and tapering to a smaller radius of curvature at the other end, a second body portion comprising a wall having an edge adapted to 10 form a continuation of the edge of the outer part of the wall of the first body portion, and curving around therefrom until it extends substantially in the same direction as that of the outer part of the first body portion, and correspondingly tapered, but of smaller curvature than that 15 of the curved surface of the first body portion, the second wall forming a second trough section, and the two together being adapted to form a cloth rolling convolute, and means yieldable to 20 hold the two trough portions together but permitting them to separate bodily one from the other in a direction in which the bottom of one trough portion moves substantially directly outwardly from the bottom of the other, said means comprising a projection extending from each 25 body portion, means joining the projections, said means being disposed outwardly from the adjoining edges of the two curved surfaces a substantial distance to provide the outward separating 30 movement aforesaid of the two trough portions, and yieldable means urging the trough portions together.

4. In a hemmer for use on material of varying thickness, a first body portion comprising a wall 35 providing a surface curved around from an outer part extending in one direction, to an inner part extending substantially in the opposite direction, to provide a first trough section, said surface having a larger radius of curvature at one end of 40 the trough and tapering to a smaller radius of curvature at the other end, a second body portion comprising a wall having an edge adapted to form a continuation of the edge of the outer part of the wall of the first body portion, and curving around therefrom until it extends substantially in the same direction as that of the outer part of the first body portion, and correspondingly tapered, but of smaller curvature than that 45 of the curved surface of the first body portion, the second wall forming a second trough section, and the two together being adapted to form a cloth rolling convolute, and means yieldable to 50 hold the two trough portions together but permitting them to separate bodily one from the other in a direction in which the bottom of one trough portion moves substantially directly outwardly from the bottom of the other, said means comprising a projection extending from each body portion, a hinge joining the projections, the hinge 55 being disposed outwardly from the adjoining edges of the two curved surfaces a substantial distance to provide the outward separating movement aforesaid of the two trough portions, yieldable means urging the trough portions together, 60 and a secondary guide wall portion on the second body portion, comprising continuation of the second curved surface around to form another trough section, said secondary guide wall being substantially wholly outside of the large end of 65 the convolute and having its end edge within the convolute sloping toward the smallest end of the convolute in a smooth curve and joining therewith.

5. In a hemmer attachment, for use in putting hems on material, a roll portion providing an

inner surface having a curve of over 180° extent to constitute means to roll the material, said roll portion being divided longitudinally into two elements having edges adapted to be brought together and said elements having complementary inner surface sections adapted to form said roll surface, means supporting the two elements for movement toward and from each other to accommodate material of different thicknesses, and

guide means on one element, extending therefrom to overlie the other element, said guide means being of a size to bridge between the elements when they are separated, having an inner surface to join the complementary surfaces of the roll portion, thereby to prevent escape of material between the separated edges of the roll portions.

GEORGE WESTHOFF.
